BOX PLEATING MACHINE

Jacob Silverman, Brooklyn, N. Y.

Application June 30, 1950, Serial No. 171,421

30 Claims. (Cl. 223—30)

1

The present invention relates to a machine for forming box pleats in fabric sheets and particularly in pockets of a type frequently used in ladies' dresses and suits.

Folding and pressing machines have in the past taken many forms. The most common type of machine is characterized by having a forming plate of a shape similar to that of the desired folded fabric object, folding members being movable over that plate to fold or bend a fabric sheet around the edges thereof, the thus folded sheet, often still on the forming plate, then being pressed so as to maintain its shape. Machines of this general type have proved quite satisfactory in many applications; but their use to form box pleats has in the past presented considerable difficulties.

By box pleats are meant sheets folded so as to have a pair of folds oriented toward one another and then reversely bent so as to extend away from one another. The edges defined by the reverse bends should, in order to present the most attractive appearance possible, be positioned as close as possible to one another, and preferably should abut one another. Adaptations of the machines in general use for pleating have been able to form box pleats but, because of the general arrangement of those machines, it has not in the past been possible to produce an optimum box pleat because the movable folding members, the inner edges of which position the edges of the reversely bent portions of the fabric sheet, were physically obstructed from moving all the way toward one another. This difficulty arose largely because of the manner of supporting the forming plate on the machine.

By a major reorganization of the parts of a pleating machine, and by the redesigning of a number of those parts, I have produced a pleating machine, here described and claimed, which has all of the attributes of speed, accuracy and convenience of operation inherent in prior art machines of the same general type but which is also capable of forming a box pleat in which the edges of the reversely bent portions are in actual contact one with the other. According to one aspect of the present invention, this has been accomplished by mounting the forming plate between a pair of pressure plates, both the forming plate and one of the pressure plates being secured to the frame of the machine at the rear ends thereof, the forming plate being movable toward one of the pressure plates, folding members of the type generally used in prior art machines interposing themselves between the forming plate and one of the pressure plates so as to

2

cause the fabric sheet to fold around the forming plate and define a box pleat. Because the forming plate is supported at its end and beyond the area thereof over which the fabric sheet is adapted to be bent, no obstruction is presented to the movement of the folding members toward one another, and hence the inner edges of the oppositely directed pleats can abut one another.

10 According to another aspect of the present invention, the above organization of parts is incorporated into a machine including a table having an aperture therein, the forming plate being below the aperture and narrower than the aperture so that the side edges of the forming plate, around which the fabric sheet is adapted to be bent, are exposed. This mode of organization makes for extreme facility in use, the fabric sheet being readily placeable under the forming plate and the edges of that sheet remaining atop the table where they may be suitably manipulated to ensure accuracy of pleat formation.

15 It is a feature of the present invention that the pressing action exerted by the machine is not exerted against the table but is instead exerted between the pressure plates, folding members and forming plate, all mounted on the table in such a manner as to provide for ease of access, positiveness of function, simplicity of construction and readiness of replaceability.

20 To the accomplishment of the above objects, and such other objects as may hereinafter appear, the present invention relates to a pleating machine particularly designed for the forming of box pleats as defined in the appended claims and as described in the specification taken together with the accompanying drawings in which:

25 Fig. 1 is a top plan view, partly broken away, of the machine of the present invention showing the parts in stand-by condition;

30 Fig. 2 is a view similar to Fig. 1 but with most of the table broken away and showing the parts in pleat-forming position;

35 Fig. 3 is an end cross-sectional view taken along the line 3—3 of Fig. 1;

40 Fig. 4 is an end cross-sectional view taken along the line 4—4 of Fig. 2;

45 Fig. 5 is a view similar to Fig. 4 but showing the lower pressure plate moved upwardly to press the formed pleat;

50 Fig. 6 is a side cross-sectional view taken along the line 6—6 of Fig. 1; and

55 Fig. 7 is a cross-sectional view showing the structure of the box pleat formed by the machine.

Having reference first to Fig. 7, the box pleat in question is formed from a fabric sheet gen-

erally designated B and comprises a bottom layer 2 and a pair of oppositely directed two-ply pleats generally designated 4 and 6, each of said pleats comprising layers 8 inwardly directed and reversely bent at edges 10 so as to define outwardly extending layers 12. The problem to which this invention is primarily directed is the formation of such a pleat in which the edges 10 of the reverse bends are as close to one another as possible, and preferably abut.

The machine of the present invention comprises a forming plate generally designated A around which a fabric sheet generally designated B is adapted to be bent through the action of folding members C, an upper pressure plate D and a lower pressure plate E being positioned above and below the forming plate A and folding members C, all these elements having relative degrees of movement such that the box pleat of Fig. 7 is first formed in the fabric sheet B and is then given a permanent set through a pressing action, preferably accompanied by heat. As an additional and very advantageous feature, a table F is provided having an aperture G therein through which access to the forming plate A is facilitated, the table F at the same time retaining the unpleated portions of the fabric sheet B in position where they may be readily manipulated. The table F has the further function of shielding the moving parts of the machine, thus preventing injury to the operator or to the fabric sheet B which is being operated upon.

The machine comprises a plate 14 suitably supported in a somewhat elevated position by means of any appropriate structure such as legs 16 which are only fragmentarily shown. The folding members C are in the form of plates 18 of some suitable slightly resilient material which have thin elongated folding edges 20 extending toward one another. The plates 18 are slidably mounted on top of the base plate 14, being provided with inclined slots 22 through which studs 24 secured to the base plate 14 pass. Pins 26 extend downwardly from the plates 18, pass through slots 28 in the base plate 14 which extend parallel to the slots 22, and are there secured to springs 30 the other ends of which are fixedly secured to pins 32 depending from the base plate 14. An actuating plate 34 is slidably mounted on the base plate 14 so as to move from front to rear thereof while engaging the front edges of the plates 18 and is provided with a bearing portion 36 against which the end 38 of actuating lever 40 bears, said lever being pivotally mounted at 42 on an ear 44 extending from the frame of the machine, secured thereto by means of screws 46. The lever 40 is provided with a manipulating handle 48 so that it can be manually pivoted from its position shown in Figs. 1 and 6 to its position shown in Fig. 2. The portion of the machine where the lever 40 is mounted will be referred to as the front thereof, since it is at that end that the operator will stand.

The forming plate A here takes the form of a relatively narrow spring leaf 50 which is secured to the base plate 14 close to the back of the machine by means of screws 52. The central portion of the base plate 14 is apertured, that aperture being defined by side edges 54, front edge 56 and rear edge 58. The leaf 50 extends along the length of this aperture in the base plate 14 and has a tip 60 which extends out beyond and above the front edge 56 of that aperture. The body of the leaf 50 constitutes its operative portion—it is over this portion that the fabric sheet B is folded to define a box pleat. That part of the leaf

50 in which the screws 52 are received constitutes its mounting portion. It will be noted that the mounting portion is to one side of the operative portion, so that the space above the operative portion is free and unobstructed.

Mounted in the aperture in the base plate 14 for vertical movement is the lower pressure plate E, here shown as formed of a metal pad 62 somewhat wider than the leaf 50 and mounted on the plate 64 to the underside of which heating elements 66 are secured by means of brackets 68, the whole being assembled together by means of screws 70. A lifting rod 72, operatively connected to a conventional lifting linkage (not shown) having an actuating lever 73 which is manually operated by a foot treadle, is secured to the lower pressure plate E so as to controllably move it upwardly when desired.

The upper pressure plate D takes the form of a thick rigid bar 74 here shown as somewhat narrower in width than the leaf 50 defining the forming plate A. The bar 74 is rigidly mounted above and spaced vertically from the leaf 50, this mounting being accomplished at the rear of the machine through the screws 76 so that the upper pressure plate D is supported in cantilever fashion, a space being defined between its lower surface and the leaf 50 along substantially the entire length of those elements. It will be noted that the thin folding edges 20 of the sliding plates 18 which define the folding members C are so vertically positioned that they are adapted to enter the space between the bar 74 and the leaf 50 (see Figs. 3 and 4), their length being such as to clear the supporting structure for the bar 74 and the leaf 50 (see Figs. 1 and 2). In other words, the plates 18 move over the operative portion of the leaf 50 in unobstructed manner but do not extend to the mounting portion thereof.

The machine of the present invention is provided with a table F defined by plate 78 secured to the base plate 14 by means of the screws 79 receivable in tapped holes 81 in the base plate 14, the plate 78 being spaced above the plate 14 by means of spacers 80 held in position on the latter by means of screws 82. The spacers 80 also serve as positive stops for the plates 18 in their retracted position. The plates 18 and 34 slide between the base plate 14 and the table plate 78 and are provided with a plurality of protrusions 84 to provide proper bearing surfaces for the plates 18 and 34 and to permit the plates 18 to be flexed upwardly for reasons hereinafter to be set forth.

The aperture G in the table F is in line with but wider than the leaf 50 defining the forming plate A. Hence the side edges of the leaf 50, around which the fabric sheet B is adapted to be bent to define the lower plies 8 of the pleats 4 and 6, are exposed. The tip 60 of the leaf 50 extends up above the table F, and a leaf spring 86 is secured to the end of the bar 74 by means of screw 88 so as to bear against the tip 60 and urge it downwardly into engagement with the front edge 56 of the aperture in the base plate 14.

Operation of the machine of the present invention is as follows: In the normal position of the elements of the machine, as shown in Figs. 1, 3 and 6, the springs 30 have retracted the plates 18 in a direction defined by the inclination of the slots 22 and 28, and they in turn have pushed the plate 34 outwardly, causing the lever 40 to rotate in a counter-clockwise direction until the plates 18 abut the spacers 80. In this position the thin folding edges 20 of the plates 18 are withdrawn so as to expose the forming plate A. That plate, be-

cause of its inherent resilience, and also because of the action of leaf spring 86 urging it downwardly, will rest on pad 62 of the lower pressure plate E; said lower pressure plate E assuming a depressed position either because of the action of gravity or any suitable biasing means. The tip 60 of the leaf 50 defining the forming plate A will extend above the level of the table F, and the aperture G in that table will expose the forming plate A.

The operator will take a fabric sheet B in which a box pleat is to be formed and will slide it from the front of the machine toward the rear so that the leading edge of the sheet B will engage under the tip 60 of the leaf 50 and will then move through and along the aperture G in the table F and under and along the leaf 50. The side edges of the fabric sheet B will remain on top of the table F, as is clearly shown in Fig. 3.

When the sheet B has been properly aligned, the operator will grasp the handle 48 on the lever 40 and rotate the lever in a clockwise direction to the position indicated in Fig. 2. This will cause the plate 34 to move rearwardly and that plate will engage the plates 18 and force them to move inwardly in a direction defined by the inclination of the slots 22 and 28, thus causing the thin folding edges 20 of the plates 18 to move toward one another and into the space between the leaf 50 and the bar 14 (see Figs. 2 and 4). Since that space is completely unobstructed the plates 18 can move inwardly until their folding edges 20 are almost in contact, separated only by the two layers of fabric therebetween. By this motion the pleat is formed, the layers 8 being defined between the plates 18 and the leaf 50 and the layers 12 being formed between the plates 18 and the bar 14. The edges 10 of the reverse bends between the layers 8 and 12 will therefore abut.

The operator will then, through a foot treadle or other linkage not here shown, cause the lower pressure plate E to move upwardly and thus press the pleated fabric sheet B between the forming plate A, the folding members C, and the pressure plates D and E, the former pressure plate being rigidly mounted in cantilever fashion on the apparatus. The nature of the material of which the plates 18 are formed permits them to flex upwardly to a sufficient degree for this pressing action to take place. The heating elements 66 facilitate the attainment of a permanent set in the material. While the lower pressure plate E is thus forced upwardly sufficient pressure will be exerted on the plates 18 as to prevent them from being retracted under the influence of the springs 30, and consequently the operator can release the handle 48 of the lever 40, thus freeing both his hands for subsequent manipulation of the fabric B.

After the pressing action has been continued for a sufficient period of time to achieve a permanent pleat, the lower pressure plate E is permitted to move downwardly, thus releasing pressure on the plates 18, which will then be automatically retracted by the springs 30. The operator then removes the fabric sheet B from the machine by pulling it toward the front thereof and out of the front portion of the aperture G in the table F.

It will be noted that in this structure the table F serves as a guide for that portion of the fabric sheet B which is unpleated, but does not directly participate in the pressing operation. The forming plate A is supported at the rear of the machine and hence the upper portion of its length is unobstructed. The upper pressure plate D is

mounted in cantilever fashion, also from the rear of the machine, and thus the space between it and the forming plate A is clear, permitting the folding edges 20 of the folding members C to move uninterruptedly all the way toward one another. As a result, the fabric sheet B may be readily placed in position for pleating and a perfect box pleat, the inner edges thereof abutting one another, will result.

It will be apparent that many variations may be made in specific details of the present machine without departing from the spirit of the invention as defined in the following claims.

I claim:

1. A pleating machine comprising a frame, a forming plate comprising an operative portion and a mounting portion at one end of said operative portion and secured to said frame, an upper pressure plate secured to said frame at a point to one side of the operative portion of said forming plate and overlying but vertically spaced from said operative portion of said forming plate, said forming plate being relatively movable toward and away from said upper pressure plate, a lower pressure plate on said frame below said forming plate, folding members mounted on said frame so as to be movable between a retracted position in which their inner edges are laterally spaced from the outer edges of the operative portion of said forming plate and an operative position in which their inner edges are moved toward one another so that said folding members are interposed between the operative portion of said forming plate and one of said pressure plates, means operatively connected to said folding members for moving them between operative and retracted positions, and means operatively connected to at least one of said pressure plates for causing relative motion of said pressure plates toward one another so as to press therebetween a fabric sheet folded around said forming plate.

2. The pleating machine of claim 1 in which said forming plate comprises a resilient leaf secured to said frame at one end only, whereby a fabric sheet may be passed thereunder in convenient manner.

3. The pleating machine of claim 1 in which said upper pressure plate is rigidly secured to said frame and said lower pressure plate is movable upwardly toward said upper pressure plate.

4. The pleating machine of claim 3 in which said forming plate comprises a resilient leaf secured to said frame at one end only, whereby a fabric sheet may be passed thereunder in convenient manner.

5. The pleating machine of claim 1 in which said upper pressure plate is rigidly secured to said frame in cantilever fashion at one end thereof and to one side of said folding members, the edges of said folding members thereby being movable into abutting relationship when said folding members are in operative position, and in which said lower pressure plate is movable upwardly toward said forming plate and said upper pressure plate.

6. The pleating machine of claim 5, in which said forming plate comprises a resilient leaf secured to said frame at one end only and to the same side of said folding members as said upper pressure plate.

7. A pleating machine comprising a frame, a table thereon having an aperture through which a fabric sheet is passable, a forming plate extending along and below said aperture substantially parallel to said table, said forming plate

comprising an operative portion and a mounting portion at one end of said operative portion and secured to said frame, said operative portion being narrower than said aperture so that the side edges thereof are exposed, an upper pressure plate secured to said frame at a point to one side of the operative portion of said forming plate and overlying but vertically spaced from said operative portion of said forming plate, the space between said upper pressure plate and said operative portion of said forming plate being free and unobstructed, said forming plate being movable substantially perpendicular to the plane of said table, a lower pressure plate on said frame below said forming plate, folding members mounted on said frame below said forming plate, so as to be movable between a retracted position in which their inner edges are laterally spaced from the outer edges of the operative portion of said forming plate and an operative position in which their inner edges are moved toward one another so that said folding members are interposed between the operative portion of said forming plate and said upper pressure plate, means operatively connected to said folding members for moving them between operative and retracted positions, and means operatively connected to at least one of said pressure plates for causing relative motion of said pressure plates toward one another so as to press therebetween a fabric sheet folded around said forming plate.

8. The pleating machine of claim 7 in which said forming plate comprises a resilient leaf secured to said frame at one end only, whereby a fabric sheet may be passed thereunder in convenient manner.

9. The pleating machine of claim 8, in which the unsecured end of said forming plate extends out of said aperture and above said table.

10. The pleating machine of claim 7 in which said upper pressure plate is rigidly secured to said frame and said lower pressure plate is movable upwardly toward said upper pressure plate.

11. The pleating machine of claim 10 in which said forming plate comprises a resilient leaf secured to said frame at one end only, whereby a fabric sheet may be passed thereunder in convenient manner.

12. The pleating machine of claim 10 in which said forming plate comprises a resilient leaf secured to said frame at one end only, the unsecured end of said forming plate extending out of said aperture and above said table.

13. The pleating machine of claim 7 in which said upper pressure plate is rigidly secured to said frame in cantilever fashion at one end thereof and the one side of said folding members, the edges of said folding members thereby being movable into abutting relationship when said folding members are in operative position, and in which said lower pressure plate is movable upwardly toward said forming plate and said upper pressure plate.

14. The pleating machine of claim 13 in which said forming plate comprises a resilient leaf secured to said frame at one end only and to the same side of said folding members as said upper pressure plate.

15. The pleating machine of claim 13 in which said forming plate comprises a resilient leaf secured to said frame at one end only and to the same side of said folding members as said upper pressure plate, the unsecured end of said forming plate extending out of said aperture and above said table.

16. The pleating machine of claim 13 in which said forming plate comprises a resilient leaf secured to said frame at one end only and to the same side of said folding members as said upper pressure plate, the unsecured end of said forming plate extending out of said aperture and above said table, and a leaf spring on the free end of said upper pressure plate engageable with the unsecured end of said forming plate and active to resiliently urge said unsecured forming plate end toward said table.

17. A pleating machine comprising a frame, a forming plate comprising a resilient leaf secured to said frame at one end only, whereby a fabric sheet may be passed thereunder in convenient manner, an upper pressure plate secured to said frame and overlying but vertically spaced from said forming plate, said forming plate being movable toward and away from said upper pressure plate, a lower pressure plate on said frame below said forming plate, folding members mounted on said frame so as to be movable between a retracted position in which their inner edges are laterally spaced from the outer edges of said forming plate and an operative position in which their inner edges are moved toward one another so that said folding members are interposed between said forming plate and one of said pressure plates, means operatively connected to said folding members for moving them between operative and retracted positions, and means operatively connected to at least one of said pressure plates for causing relative motion of said pressure plates toward one another so as to press therebetween a fabric sheet folded around said forming plate.

18. A pleating machine comprising a frame, a forming plate movably secured thereto, an upper pressure plate rigidly secured to said frame and overlying but vertically spaced from said forming plate, said forming plate being movable toward and away from said upper pressure plate, a lower pressure plate on said frame below said forming plate and movable upwardly toward upper pressure plate, folding members mounted on said frame so as to be movable between a retracted position in which their inner edges are laterally spaced from the outer edges of said forming plate and an operative position in which their inner edges are moved toward one another so that said folding members are interposed between said forming plate and one of said pressure plates, means operatively connected to said folding members for moving them between operative and retracted positions, and means operatively connected to at least one of said pressure plates for causing relative motion of said pressure plates toward one another so as to press therebetween a fabric sheet folded around said forming plate.

19. A pleating machine comprising a frame, a forming plate comprising a resilient leaf secured to said frame at one end only, whereby a fabric sheet may be passed thereunder in convenient manner, an upper pressure plate rigidly secured to said frame and overlying but vertically spaced from said forming plate, said forming plate being movable toward and away from said upper pressure plate, a lower pressure plate on said frame below said forming plate and movable upwardly toward said upper pressure plate, folding members mounted on said frame so as to be movable between a retracted position in which their inner edges are laterally spaced from the outer edges of said forming plate and an opera-

tive position in which their inner edges are moved toward one another so that said folding members are interposed between said forming plate and one of said pressure plates, means operatively connected to said folding members for moving them between operative and retracted positions, and means operatively connected to at least one of said pressure plates for causing relative motion of said pressure plates toward one another so as to press therebetween a fabric sheet folded around said forming plate.

20. A pleating machine comprising a frame, a forming plate movably secured thereto, folding members mounted on said frame so as to be movable between a retracted position in which their inner edges are laterally spaced from the outer edges of said forming plate and an operative position in which their inner edges are moved toward one another so that said folding members overlie said forming plate, an upper pressure plate rigidly secured to said frame in cantilever fashion at one end thereof and to one side of said folding members, the edges of said folding members thereby being movable into abutting relationship when said folding members are in operative position, a lower pressure plate on said frame below said forming plate and movable upwardly toward said forming plate and said upper pressure plate, means operatively connected to at least one of said pressure plates for causing relative motion of said pressure plates toward one another so as to press therebetween a fabric sheet folded around said forming plate.

21. The pleating machine of claim 20 in which said forming plate comprises a resilient leaf secured to said frame at one end only and on the same side of said folding members as said upper pressure plate.

22. A pleating machine comprising a frame, a table thereon having an aperture through which a fabric sheet is passable, a forming plate comprising a resilient leaf secured to said frame at one end only, whereby a fabric may be passed thereunder in convenient manner, said leaf extending along and below said aperture substantially parallel to said table, said leaf being narrower than said aperture so that the side edges of said leaf are exposed, an upper pressure plate secured to said frame and overlying but vertically spaced from said leaf, said leaf being movable substantially perpendicular to the plane of said table, a lower pressure plate on said frame below said leaf, folding members mounted on said frame below said leaf so as to be movable between a retracted position in which their inner edges are laterally spaced from the outer edges of said leaf and an operative position in which their inner edges are moved toward one another so that said folding members are interposed between said leaf and said upper pressure plate, means operatively connected to said folding members for moving them between operative and retracted positions, and means operatively connected to at least one of said pressure plates for causing relative motion of said pressure plates toward one another so as to press therebetween a fabric sheet folded around said leaf.

23. The pleating machine of claim 22, in which the unsecured end of said leaf extends out of said aperture and above said table.

24. A pleating machine comprising a frame, a table thereon having an aperture through which a fabric sheet is passable, a forming plate secured to said frame and extending along and below said aperture substantially parallel to said

table, said forming plate being narrower than said aperture so that the side edges of said forming plate are exposed, an upper pressure plate rigidly secured to said frame and overlying but vertically spaced from said forming plate, said forming plate being movable substantially perpendicular to the plane of the table, a lower pressure plate on said frame below said forming plate and movable upwardly toward said upper pressure plate, folding members mounted on said frame below said forming plate so as to be movable between a retracted position in which their inner edges are laterally spaced from the outer edges of said forming plate and an operative position in which their inner edges are moved toward one another so that said folding members are interposed between said forming plate and said upper pressure plate, means operatively connected to said folding members for moving them between operative and retracted positions, and means operatively connected to at least one of said pressure plates for causing relative motion of said pressure plates toward one another so as to press therebetween a fabric sheet folded around said forming plate.

25. The pleating machine of claim 24, in which said forming plate comprises a resilient leaf secured to said frame at one end only, whereby a fabric sheet may be passed thereunder in convenient manner.

26. The pleating machine of claim 24, in which said forming plate comprises a resilient leaf secured to said frame at one end only, the unsecured end of said forming plate extending out of said aperture and above said table.

27. A pleating machine comprising a frame, a table thereon having an aperture through which a fabric sheet is passable, a forming plate secured to said frame and extending along and below said aperture substantially parallel to said table, said forming plate being narrower than said aperture so that the side edges of said forming plate are exposed, folding members mounted on said frame so as to be movable between a retracted position in which their inner edges are laterally spaced from the outer edges of said forming plate and an operative position in which their inner edges are moved toward one another so that said folding members overlie said forming plate, an upper pressure plate rigidly secured to one end thereof in cantilever fashion to said frame and to one side of said folding members so as to overlie and be vertically spaced from said forming plate, the edges of said folding members thereby being movable into abutting relationship when said folding members are in operative position, said forming plate being movable substantially perpendicular to the plane of said table, a lower pressure plate on said frame below said forming plate and movable upwardly toward said forming plate and said upper pressure plate, means operatively connected to said folding members for moving them between operative and retracted positions, and means operatively connected to at least one of said pressure plates for causing relative motion of said pressure plates toward one another so as to press therebetween a fabric sheet folded around said forming plate.

28. The pleating machine of claim 27, in which said forming plate comprises a resilient leaf secured to said frame at one end only and to the same side of said folding members as said upper pressure plate.

29. The pleating machine of claim 28, in which

the unsecured end of said forming plate extends out of said aperture and above said table.

30. The pleating machine of claim 28, in which the unsecured end of said forming plate extends out of said aperture and above said table, and in which a leaf spring is provided on the free end of said upper pressure plate engageable with the unsecured end of said forming plate and active to resiliently urge said unsecured forming plate end toward said table.
